UNITED STATES PATENT OFFICE.

VICTOR H. EMERSON, OF NEW YORK, N. Y., ASSIGNOR TO EMERSON PHONOGRAPH COMPANY, INC., OF NEW YORK, N. Y., A CORPORATION OF NEW YORK.

SOUND RECORD AND METHOD OF PRODUCING THE SAME.

1,416,342.

Specification of Letters Patent. Patented May 16, 1922.

Application filed April 20, 1920. Serial No. 375,243.

To all whom it may concern:

Be it known that I, VICTOR H. EMERSON, a citizen of the United States, residing at the city, county, and State of New York, have 5 invented new and useful Improvements in Sound Records and Methods of Producing the Same, of which the following is a specification.

My invention relates to phonograph records and methods for their production, and has for an object economically to produce a device of the class described having increased durability and efficiency.

Another object of my invention more particularly described is to form a composite phonograph record having superior reproducing qualities due to the peculiarly adaptable properties of certain of the elements employed in practising my invention.

20 Numerous attempts have been made to fabricate a commercial record of different materials with a view to cheapening its manufacture and otherwise attempting to improve upon this type of record, and to this 25 end such records have, for example, been made up in layers, i. e., with a layer of record material, so called, reinforced by a body portion of different composition, such as paper or materials possessing similar properties.

Thus a variety of laminated records have heretofore been brought out with varying success as to practical and wearing results, many of them possessing serious defects due 35 to the fact, among other considerations, that in the present state of the art the commercial record in the final stage of its manufacture must receive its grooved record face by action of a matrix stamper impressed with 40 great force into the surface of the blank of which the record is formed. Hence, it is highly important to have the entire substance or body portion of the blank of material that will not only withstand the high 45 pressure incident to the stamping operation referred to, but will rigidly present the record surface to the stampers and support the same in such firm manner that all the minute irregularities or sound undulations of the 50 material shall be imprinted to their full depth and with the greatest attainable accuracy; and furthermore it is important not only that the irregularities representative of sound waves be accurately recorded, but that

the record thus made shall be permanently 55 retained by the medium into which those irregularities are indented precisely to the full depth and width of the sound waves which they represent, if maximum efficiency be attained.

60 The pressure resisting and form sustaining features of a record blank having been supplied as described, an important element remains to be attained in the matter of securing firmly upon such body portion the 65 layer of record material which must be fixed in such intimate relationship therewith that the record surface will not form fissures or separate itself from the supporting layer or body portion of the record.

70 These generic objects will be accomplished in the use of my improved method, and the record thereby produced will have the general characteristics described, but I have introduced other features which as far as I am 75 aware have not heretofore been employed in the production of a commercial phonograph record, namely, features comprising among others the employment of a layer or layers 80 possessing the properties and characteristics of certain metals and having record material upon the outer or top surface, and upon the opposite face of the metal disk a second disk is added similar in form but of a relatively yielding material sufficient to permit the 85 rigid non-yielding metal portion to conform to the general surface contour of the matrix, notwithstanding that such metal sheet although thus cushioned retains sufficient stiffness and rigidity to receive all of the matrix 90 undulations, however minute and delicate they may be.

95 In its broad aspects my invention therefore comprises as an indispensable element the unyielding layer possessing the characteristics of the harder metals employed in the manner described and as a contributing feature to facilitate the process of the manufacture of my improved record, under specified conditions there is applied to the metallic 100 body the additional or under layer of relatively yielding non-record material above referred to. Hence, the metal thus coacting with its under or cushioning layer disk, not only sustains the thin veneer of record material in form and position most effectual for receiving the pressing operation of the stamper or matrix, but also because of its 105

underlying layer of relatively reduced rigidity, conforms to the general contour of the stamper.

Furthermore, in the practice of my improved process, as pointed out, I employ as one of its features suitable means for effecting an intimate and permanent union of the thin deposit of record material directly to the metal surface. Although the record material may be applied upon one face of the metal plate, and the non-record or cushion material on the others in any convenient way, in conformity to the general scope of my invention, but preferably in the employment thereof I previously treat the respective surfaces of the metal plate, the one face for receiving the record material, the other for receiving the pad or paper layer, with an acid or other corrosive agent that will slightly roughen these surfaces so as to cause a more firm and permanent union of the specified materials with the metal, as described. The depth of the irregularities thus formed in the metallic surfaces will obviously depend upon the length of time the expansion to the contact continues and one familiar with the requirements to make a record usable and commercial will readily determine the period necessary properly to prepare the surface of the metallic layer for the reception of record material or the subsidiary layer.

It is apparent that in pressing a record blank with a metallic disk employed as a component in the manner described, if the metal plate be of uniform gage of thickness and if its under side, during the pressing of a matrix thereon, rests upon a perfectly flat surface base, then, in order to obtain practical results the surface of the matrix should be disposed in accurate correspondence therewith. Thus, should the engaging surface plane of the matrix plate not conform in exact parallelism with that of the face of the disk to be stamped thereby, the face of the matrix would be mashed into flat conformity to the plane or level of the base plate upon which the record blank is resting at the moment. Hence, even though such variation between the respective surfaces of the stamper and blank be extremely slight, irreparable damage might be caused to the face of the matrix owing to the unyielding property of the metal, were some provision not made to compensate for any such un conformity.

To overcome this difficulty I place a layer of cardboard or other relatively firm material which will yield only to an extent sufficiently to conform to the contour or general level of the face of the matrix, or of the two matrices when a double disk is pressed, as will presently be more fully described.

The foregoing description relates to the formation of a record having sound undula-

tions upon a single face. When a double faced record is made in accordance with my improved method I employ two metal plates separated by the relative yielding layer above described as an under or cushioning disk. The metal disks will each have one surface prepared with a coating of record material in the manner above described, and the reverse faces of the disks thus brought together form a single blank, but are separated by the relatively yielding or compressible layer.

The separating layer will thus act as a pad or cushion to absorb or compensate for any under pressure caused by unevenness of either or both of the matrix plates when pressure of the matrix press has been applied in the process of stamping the record.

Having reference to the drawings illustrative of a preferred form of the embodiment of the record of my invention and apparatus employed in the process of its manufacture,—

Figure 1 represents the top surface of a metal disk showing a pitted surface partly covered with record material laid thereon.

Fig. 2 is an enlarged edge view of the disk shown in Fig. 1.

Fig. 3 is the representation of a type of press for impressing matrices upon the opposite faces of a record, with record materials, shown greatly exaggerated, in a preparatory position for pressing.

Fig. 4 is a view, also enlarged, of the record components shown in Fig. 3 immediately after pressing has been applied forming a record.

Fig. 5 is an enlarged partial view of the record as shown in Fig. 4 having had its rough edges removed.

Referring to the illustrations: The numeral 1 represents a disk of thin metal which because of the relative inexpensiveness of sheet steel, may preferably be of that metal, having roughened surfaces upon its respective faces upon a portion of the top surface of which is shown a fragmentary layer of record material 3 having sound grooves 4 impressed therein and the usual central orifice 5 shown therethrough.

The record material 3 comprising the usual earthy material, shellac and the other ingredients familiar to those engaged in the making of sound records, may be laid over the surface of the metal sheet in any convenient way, in the form of so-called record dust to an even depth, as shown in Figs. 1 and 2, and fixed thereto by means of any adhesive agent by japanning or by applying sufficient heat directly to the material, or as a mass to be flattened out by the pressure of the matrix stamper. In almost any form applied the metal plates will retain the recording layer more effectually if the adjacent surface has first been pitted, even

though only slightly roughened, for the record material will thus seek out and enter the infinitely small and numerous cavities thereby forming a much more neatly integral 5 union with the metal base.

A further advantage to be found in the employment of the metal plate with a surface provided with minute irregularities resulting from corrosion, in the manner described, is the minimizing of the tendency to 10 mash down the protuberances of the ridged surface of the matrix plate, if brought with sufficient force against a perfectly smooth and hard metallic surface such as that of a 15 disk of sheet steel.

I therefore employ in the preferred form of my improved process as preliminary steps thereof the preparation of a disk plate of thin metal, preferably formed 20 of sheet steel of substantially the diameter of the record to be made therefrom, having a centering orifice 5. The disk is then immersed in a bath of a suitable corrosive mixture for a predetermined exposure to the 25 action thereof, after which all traces of the acid are removed from the disk surface. I next apply upon one face of the metal disk a layer of record material uniformly to the desired depth, preferably in a finely powdered form, and slightly heat the plate with its dusted layer until it becomes sufficiently 30 plastic to adhere to the surface.

I next prepare a disk 6 of thick paper or cardboard of slightly greater diameter than 35 the metal disk 1, as shown best in Fig. 4, and having the same central orifice 5, to which paper disk I apply a coating 7 of shellac or varnish, or any convenient thermo-plastic agent, as shown in exaggerated form 40 in Fig. 3, and place the sheet metal disk concentrically thereon, as shown in Fig. 1.

Thus combined, my record in its simplest form, i. e., for making a single faced record, is ready to be submitted to the stamping 45 process or pressing step of my improved process; but as already pointed out, I contemplate forming sound records having photographic records upon both of their faces, and, therefore, I add the coating of thermo- 50 plastic adhesive material 7 to the surfaces of the paper disk 6 and in the manner described apply the metal disks 1, both of which have been prepared in the manner described, and with the three disks thus arranged with their orifices 5 in axial or concentric alignment, they are centered upon the pin 12 of the matrix 10 of the press 9 which has a matrix 11 secured to the upper plate 8 of the press.

60 In connection with the simple form of press 9 illustrated in the drawings, means are shown for introducing a heating medium for softening the record material and the other thermo-plastic constituents employed 65 in building up the record blank. Thus the

bed plate 8 has the respective intake and discharge pipes 12 and 12^a while the upper plate 8^a has like connections 13 and 13^a which may be employed for conducting steam or other medium for introducing heat into the 70 upper and lower plates of the press for the purpose above explained. However, any suitable type of press may be used so long as the required degree of heat may be imparted to the thermo-plastic materials 75 immediately preceding the application of pressure in forming the record, the particular form thereof being no part of my invention.

When the layers have been thus subjected to the required heat and pressure a surplus 80 of the respective plastic materials will exude around the edge and form a rim 14 upon the peripheries of the disks wholly or partially concealing the laminated construction of the record, and which rough or rounded edge as a final operation of my process is ground off after having become 85 sufficiently hardened for the purpose.

Having described my invention, what I 90 claim is:

1. A method for forming sound records which comprises the following steps; preparing a thin metal disk, roughening the surfaces of the disk and applying record material directly to one surface and a disk of 95 cardboard to the other surface thereof.

2. A method for forming sound records upon a metallic disk which consists in applying a layer of record material directly to one surface and a disk of cardboard to 100 the other of said surfaces.

3. A method for forming sound records upon a metal disk by means of corroding the surfaces thereof, applying a layer of thermo-plastic record material directly to 105 one surface and attaching a disk of relatively yielding material to the other surface thereof.

4. A method for forming sound records upon a metal disk by means of corroding 110 the surfaces of the metal and applying a layer of thermo-plastic record material directly to one surface and attaching a disk of relatively yielding material to the other surface thereof by means of a thermo-plastic 115 material.

5. A method for forming sound records which consists in preparing a disk of thin metal, corroding the surfaces thereof and adding a layer of record material directly 120 to one of the surfaces, coating the other surface of the said disk with a thermo-plastic material and applying thereto a disk of cardboard, submitting the disks thus prepared to a matrix press, applying sufficient heat to 125 render plastic said materials, and pressing said matrix into said layer of record material.

6. A method for forming sound records which consists in preparing a metal disk, 130

- roughening the surfaces thereof and dusting a layer of powdered thermo-plastic record material directly upon one of said surfaces, applying sufficient heat to cause said record material to adhere to said surface, then applying a layer of relatively yielding material to the other surface of the metal disk by means of thermo-plastic material, and submitting the disks thus prepared to heat and pressing upon the surface having record material thereon a matrix of a sound record.
7. A method for forming sound records which consists in preparing disks of metal and cardboard having similar central orifices and uniting them by means of a suitable adhesive medium and applying record material directly to the exposed surface of the metal disk.
8. A method for forming sound records which consists in preparing disks of metal and cardboard having similar central orifices and uniting them by means of a suitable adhesive medium and applying record material directly to the exposed surface of the metal disk by heat and pressure and indenting a sound groove therein.
9. A method for forming sound records which consists in preparing two similar disks of metal and a similar disk of cardboard, attaching the metal disks to the respective faces of the cardboard, applying record material directly to the outer faces of the metal disks and pressing sound matrices thereon.
10. A method for forming sound records consisting in preparing two similar disks of metal, roughening their surfaces by corrosion, preparing a disk of cardboard of suitable thickness and applying thermo-plastic material to the faces of the paper, placing said metal disks upon the surfaces thereof, applying a layer of thermo-plastic record material to the outer surfaces of the metal disks and submitting the disks thus prepared to heat and pressure and stamping sound record grooves in said layers.
11. A sound record comprising a disk layer of metal and of paper of suitable thickness, means comprising thermo-plastic material for causing said layers to adhere together, and a layer of thermo-plastic record material directly upon said metal disk having a sound record impressed thereon.
12. A sound record comprising a metal disk with a coating of record material thereon, said metal disk having at its opposite 85 face a disk formed of relatively yielding material.
13. A sound record comprising a disk layer of metal superimposed upon a disk of relatively yielding material, thermo-plastic 60 means for securing said disks together and a thermo-plastic layer of record material directly upon said metal disk having a groove thereon containing undulations representative of sound waves.
14. A sound record comprising a layer of thermo-plastic record material upon a metal disk superimposed upon a similar disk of paper of suitable thickness secured thereto by thermo-plastic material directly and a 70 sound record impressed in said record material.
15. A sound record having layers of metal and a layer of record material intimately 75 united to the metal.
16. A sound record having a layer of metal and a layer of thermo-plastic record material intimately united to a surface of the metal.
17. A sound record having a disk of metal 80 with a pitted surface and a layer of record material pressed into said surface and a sound groove pressed into said material.
18. A sound record having a disk of metal with a pitted surface, a layer of record material upon said pitted surface and a cushion disk attached to said metal disk.
19. A sound record disk having metal disks with pitted surfaces, record material in their layers intimately attached to a surface of said metal disks and a cushioning 90 layer between said metal disks.
20. A sound record comprising a disk of relatively hard material with record material permanently attached thereto and a 95 cushion layer attached to said disk.
21. A sound record comprising a disk of relatively hard material having roughened surfaces, said disk imposed upon a layer of yielding material and having a layer of 100 record material with irregularities representative of sound waves thereon.

In testimony whereof I have hereunto set my hand.

VICTOR H. EMERSON.
